RAILWAY TRAFFIC CONTROLLING
APPARATUSEarl M. Allen, Swissvale, Pa., assignor to The
Union Switch & Signal Company, Swissvale,
Pa., a corporation of Pennsylvania

Application November 5, 1938, Serial No. 239,081

24 Claims. (Cl. 246—3)

My invention relates to railway traffic controlling apparatus, and more particularly to centralized traffic controlling systems for railroads.

In systems of this character, it is customary to control the track switches and signals from a central point, usually the train dispatcher's office, and to indicate the condition of the trackway apparatus at the office, by means of impulse codes transmitted over line wires extending from the office to each of a plurality of field stations in turn, the same line wires being also used for the automatic transmission of "OS" codes indicating the movement of trains past the several stations.

One object of my invention is the provision of means for enabling the operator at the control office to selectively render the apparatus at any field station inactive. In accordance with this feature of my invention the signals are arranged to clear automatically to permit train movements past the inactive stations without further attention and the transmission of all indication codes except the "OS" codes from such stations is suspended, thereby greatly decreasing the number of codes per train movement and also decreasing the demands upon the operator's time, permitting the communication system to be extended to include a much larger territory than heretofore.

Another object of my invention is the provision of an improved absolute permissive block system for a single track railway provided with passing sidings, in which the signals clear automatically to permit train movements in either direction.

Other objects, features and purposes of my invention will appear as the description progresses.

I shall describe two forms of apparatus embodying my invention, and shall then point out the novel features thereof in claims.

Referring to the accompanying drawings, Figs. 1A, 1B and 1C are diagrammatic views showing trackway apparatus embodying one form of my invention. A complete unit of the trackway portion of this form of my invention may be illustrated by placing these views end to end in order with Fig. 1A at the left, and the system may be further extended by placing additional copies of Figs. 1A, 1B and 1C in that order at the right of Fig. 1C.

Fig. 2 shows in diagrammatic form a portion of a communication system arranged to control the apparatus of Figs. 1A, 1B and 1C from a central office. Figs. 3A and 3B are diagrammatic views showing the trackway apparatus for a second form of my invention. A complete unit of

this form of my invention may be illustrated by placing Figs. 3A, 3B and 1C end to end in order with Fig. 3A at the left, and the system may be further extended by placing additional copies of Figs. 3A, 3B and 1C in that order at the right of Fig. 1C.

Similar reference characters refer to similar parts in each of the several views.

Referring to Figs. 1A, 1B and 1C, the diagram at the top represents a stretch of single track railway including a passing siding. Each track is indicated conventionally by a single line, and it is to be understood that the track rails are divided by insulated joints into track sections as identified by the references T with distinguishing numerical prefixes, each track section being provided with the usual closed track circuit having a source of current B connected across the rails at one end and a normally energized track relay TR at the other end.

The point at which the track switch 1 of Fig. 1A is located is identified as station No. 1 of the centralized traffic control system, the circuits and apparatus shown in Fig. 1A being that required for the control of the track switch 1, of the head block signals 2RA and 2LA governing main line train movements over the switch, and of the slow speed signals 2RB and 2LB governing train movements into and out of the siding. It is to be understood that the circuits and apparatus at station No. 2 at the opposite end of the siding, which are illustrated in Fig. 1B, are similar except for the fact that corresponding line circuits extend in the opposite direction. Fig.

1C shows the circuits for the intermediate automatic signals 10, 11, 12 and 13 located in the single track stretch between two sidings. Since the circuits for the two directions of traffic are similar, it is deemed that a description of the circuits for one direction will suffice for a clear understanding of the complete system.

Referring to Fig. 1A, the track switch 1 is provided with the usual dual-control switch machine 1SM which may be operated by power to normal or reverse by energizing a polarized switch control relay 1WR in a corresponding direction. The switch machine has a selector lever 1DS by means of which the switch may be disconnected from the power mechanism and coupled to a hand-throw mechanism for local operation by means not shown, lever 1DS also controlling a relay 1WL in such a manner that relay 1WL is energized when switch 1 is conditioned for power operation and is deenergized when it is conditioned for hand operation. The switch machine

is also provided with the usual indication circuit controller controlling a polarized switch indication relay 1WP which is energized in the normal or reverse direction only when switch 1 is closed 5 and locked in its normal or reverse position, respectively, as indicated in Fig. 1A. Relays 1WR and 1WP jointly control two indication repeating relays 1NWP and 1RWP in such a manner, as will be apparent from the circuits shown at the 10 bottom of Fig. 1A, that each normal or reverse repeating relay when energized indicates that switch 1 is closed and locked in a corresponding normal or reverse position in agreement with the position of the polar contacts of the switch control relay 1WR.

The signals may be of any suitable type, but as shown they may be understood to be of the searchlight type, each having a mechanism of the form disclosed in the E. J. Blake Reissue 20 Patent No. 14,940 of August 31, 1920. Each signal mechanism is identified by the reference G with distinguishing prefix, and each is lighted by a lamp E also identified by a prefix corresponding to the designation of the signal with 25 which it is associated. Each signal which is arranged for full automatic operation is provided with a fixed marker signal M containing a lamp ME.

Under centralized traffic control operation, the 30 track switch and the signals of Fig. 1A are governed manually by means of a group of five control relays, such as the stick relays 1NWS, 1RWS, 2LHS and 2US shown at the right in Fig. 2, which relays are actuated by means of 35 codes transmitted from the office, as hereinafter will be explained. Normally, however, as already mentioned, the manual control apparatus is inactive and the system functions as an automatic block system of the absolute-permissive type. In 40 the inactive condition, the track switch at each station is maintained in its normal position as shown and the code controlled relays NWS and US are held energized over their stick circuits, the remaining code controlled relays being de- 45 energized. Each relay US completes a circuit for energizing a conditioning relay AB, which relay determines the active or inactive condition of the station apparatus. Relay AB is energized, as shown, to render the station apparatus 50 inactive, over a circuit which may be traced in Fig. 2 from the positive or supply terminal B of a suitable local source of current, front contact 11 of relay 2US, back contacts 12 and 13 of relays 2LHS and 2RHS, normal contact 14 55 of the switch indication relay 1WP, relay 2AB to the negative or common return terminal C of the same source.

Referring now to Figs. 1A, 1B and 1C, the 60 apparatus as shown is in its normal inactive condition, and its operation as an automatic block system will now be described in detail, with reference to train movements from left to right.

In Fig. 1A it will be seen that the lamps 2RAE and 2RBE for the signals 2RA and 2RB are 65 lighted and that these signals are both at stop. Signal 2RB is at stop because the circuit for its mechanism 2RBG is open at contact 15 of the reverse switch indication relay 1RWP and at front contact 31 of the control relay 2RHS. 70 while signal 2RA is a stop because the circuit for its mechanism 2RAG is open at contact 18 of a normally energized approach relay 2RAR. The polarity of the current supplied to the mechanism G for each main line signal is controlled 75 by a pole changer relay P controlled by the

mechanism G for the next signal in advance, mechanism 2RAG, for example, being controlled by the pole changer relay 4RAP controlled by mechanism 4RAG as shown in Fig. 1B, so that when the circuit for mechanism 2RAG is closed, 5 signal 2RA will indicate proceed if the advance signal 4RA indicates proceed or caution and will indicate caution if signal 4RA indicates stop. For each main line signal a directional stick relay LS or RS is provided, which relay becomes 10 energized when a train passes the corresponding signal at clear, the function of these relays being to maintain the established traffic direction under certain conditions as hereinafter pointed out. Thus signal 2LA, governing traffic movements from right to left has associated therewith a directional stick relay 2LS, which relay has a back contact 18 in the circuit for mechanism 2RAG. 15

Each signal mechanism or group of mechanisms controls an approach locking stick relay such as the relays 2RAS and 2LAS. The circuits for the relays AS are arranged in a well-known manner as shown, for example, in the Wallace Patent No. 1,959,072, granted May 15, 25 1934, to provide the usual time and approach locking of the switch and of opposing signals. It is to be understood that these relays are preferably controlled in such a manner that when a signal is manually put to stop, the energization 30 of the associated relay AS is delayed for a measured time interval provided an approach relay AR governed by front contacts of the track relays of an approach zone in advance of the signal is deenergized, this delay being nullified 35 if the signal is put to stop automatically by a passing train or if the approach zone is unoccupied. To simplify the drawings the circuits for the relays AS are not shown in detail further than to indicate by dotted line connections that each is energized only when the corresponding signals indicate stop and the distant signal in the rear indicates stop or caution.

Thus for example, a circuit for relay 2LAS extends from terminal B at back contact 20 or 45 reverse contact 21 of mechanism 4LAG, shown at the lower left in Fig. 1B and closed when signal 4LA indicates stop or caution, respectively, thence to Fig. 1A and over back contacts 22 and 23 of mechanisms 2LAG and 2LBG, closed 50 when signals 2LA and 2LB indicate stop, over other contacts, not shown and then through the winding of relay 2LAS to terminal C. Relay 2LAS when released locks the track switch 1 by opening its front contact 24 in the circuit 55 for the switch control relay 1WR and locks signals 2RA and 2RB by opening its front contact 25 in the circuits for mechanisms 2RAG and 2RBG.

The track relay 1TR at its contact 26 completes a circuit for a slow acting repeater relay 1TZ, and relays 1TZ and 1TR have front contacts 27 and 28 in the circuits for mechanisms 2RAG and 2RBG. When the manual control is inactive, as shown, the caution circuit for signal 60 2RA, which will now be traced, extends from terminal B, back contact 29 of relay 4RAP, front contact 30 of relay 1NWP, mechanism 2RAG, over contacts 16 to 19 of relays 1NWP, 2AB, 2RAR and 2LS, respectively, back contact 31 of 70 relay 2RHS, front contacts 25, 27 and 28 of relays 2LAS, 1TZ and 1TR, back contact 32 of relay 1RWP, front contacts 33 and 34 of track relays 2TR and 4TR for sections 2T and 4T, contact 35 of the dual selector relay 3WL for 75

switch 3, contact 36 of the track relay 3TR for the switch section 3T, contact 37 of the approach locking relay 4LAS, contact 38 of relay 4RAP to terminal C. When switch 3 is reversed, contacts 36 and 37 are bridged by the reverse contact 39 of the switch indication relay 3WP, and it will be seen, therefore, that when switch 3 is reversed, the control limit of signal 2RA extends only to the next signal 4RA in advance, but that when switch 3 is normal, as shown, it extends to the opposing signal 4LA and the circuit for signal 2RA is then checked by including therein the front contact 37 of the approach locking relay 4LAS governed by the opposing signals 4LA and 13.

Since mechanism 2RAG is deenergized normally, the circuit for the pole changer relay 2RAP is normally open at contact 40 of mechanism 2RAG, and the caution circuit for the next signal 10 in the rear may be traced by placing Fig. 1C at the left of Fig. 1A. This circuit extends from terminal B, back contact 41 of relay 2RAP, mechanism 10G, contacts 42, 43 and 44 of the track relays 10TR, A10TR and 1TR, contact 45 of relay 2LAS, back contact 46 of relay 2RAP to terminal C. It will be seen that the control limit of signal 10 extends to the opposing signal 2LA or 2LB in advance and its circuit is checked by including therein contact 45 of the approach locking relay 2LAS governed by the opposing head block signals 2LA and 2LB and by the distant signal 4LA.

The mechanism for signal 10 is therefore in a position to indicate caution, but this signal is approach lighted and its lamp 10E and also the marker lamp 10ME are normally dark, the circuits for these lamps being open at contact 47 of an approach lighting relay 10AE and at contact 48 of relay 11P associated with the opposing signal 11, as will be apparent from Fig. 1C. The circuit for relay 10P is, however, completed by mechanism 10G at its contact 49 so that the clear circuit for the next automatic signal 12 in the rear is closed from terminal B, through the winding of relay 10AE, contact 50 of relay 10P, back contact 51 of the opposing directional stick relay 11S, front contacts 52 and 53 of track relays 11TR and 12TR, mechanism 12G, contact 54 of relay 10P to terminal C.

Mechanism 12G therefore is normally in the clear position, but this signal is also approach lighted and the circuits for lamps 12E and 12ME are open at contacts 55 and 56 of relays 12AE and 13P. The circuit for relay 12P is closed by mechanism 12G at its contact 57 and relay 12P is energized to prepare the clear circuit for the next signal 4RA in the rear of signal 12. By placing Fig. 1B at the left of Fig. 1C, this circuit may be traced from terminal B, relay 12AE, contact 58 of relay 12P, back contact 59 of the opposing directional stick relay 13S, contacts 60, 61, 62 and 63 of the track relays 13TR, A13TR, 3TR and the repeating relay 3TZ, contact 64 of relay 4LAS, back contacts 65 and 66 of the signal control relay 4RHS and of the opposing directional stick relay 4LS, back contact 67 of the approach relay 4RAR, front contacts 68 and 69 of relays 4AB and 3NWP, mechanism 4RAG, contact 70 of relay 12P to terminal C.

Signal 4RA is lighted by a lamp having a circuit similar to that shown for lamp 2LAE in Fig. 1A for the similar signal 2LA and signal 4RA will, therefore, indicate stop, its control circuit being open at contact 67 of relay 4RAR.

I shall now trace the progress of a train mov-

ing from left to right over the tracks of Figs. 1A, 1B and 1C, starting with the condition that the train occupies section 4T. Relay 4TR, and consequently relay 4RAR will be released, completing the circuit for mechanism 4RAG at contact 67 so that signal 4RA will indicate clear. If now the train enters section 3T, contacts 62 and 63 of relays 3TR and 3TZ in the circuit for signal 4RA will open, and consequently relay 12AE which is included in series in that circuit will be released. The circuit for mechanism 13G, which extends from Fig. 1B to Fig. 1C at the right, and is similar to that for mechanism 10G already described, will be open at contact 71 of relay 3TR, and contact 72 of mechanism 13G will be open so that relay 13P is released. It follows that contacts 55 and 56 of relays 12AE and 13P are both closed, completing a circuit to light the lamps 12E and 12ME, causing signal 12 in advance of the approaching train to indicate clear. As the train proceeds, the opening of contacts 61 and 172 of relay A13TR and of contacts 60 and 73 of relay 13TR, respectively, will maintain this condition until the train enters section 12T, whereupon the closing of back contact 74 of relay 12TR completes a pick-up circuit momentarily over front contact 75 of relay 12P to energize the directional stick relay 12S. Relay 12TR at contact 53 opens the series circuit for mechanism 12G and relay 10AE. Mechanism 12G releases and by opening contact 57 releases relay 12P. Relay 12P upon releasing completes the stick circuit for relay 12S at back contact 75, and at its back contacts 70 and 58 prepares the caution control circuit for signal 4RA including contacts 76 and 77 of relay 12S, which circuit will be completed when the train vacates section 13T.

Since relay 13P is released, its front contacts 78 and 79 in the circuit for mechanism 11G are open and since the front contacts of relay 13S are also open, it follows that mechanism 11G is deenergized, its contact 80 is open and relay 11P is released, and contact 48 of relay 11P in the circuit for lamps 10E and 10ME is closed. When the train enters section 12T, the release of relay 10AE therefore completes the lighting circuit for signal 10 at its contact 47, causing signal 10 in advance of the train to indicate caution.

Since relay 11P is released, front contacts 81 and 82 are open, and since the front contacts of relay 11S in the circuit for mechanism 2LAG are open, signal 2LA is prevented from clearing.

When the train enters section 11T, the normally closed circuit for relay 2RAR which includes the front contacts 83, 84 and 85 of the track relays 11TR, 10TR and A10TR is opened, and relay 2RAR releases to complete at contact 18 the caution circuit for mechanism 2RAG already traced. Signal 2RA therefore is caused to indicate caution, and contact 40 closes, energizing relay 2RAP to reverse the pole changer contacts 41 and 46 to change the indication of signal 10 from caution to clear. Relay 2RAS now releases, its circuit being opened at contact 86 of mechanism 2RAG and also at contacts 87 and 49 of mechanism 10G. Relay 2RAS opens contacts 88 and 89 in the circuits for the opposing signal mechanisms 2LAG and 4LAG, and also opens contact 90 in the circuit for relay 4RAR, and contact 91 in the circuit for relay 1WR.

When the train enters section 10T, mechanism 10G and relay 10P become deenergized and the directional stick relay 10S becomes energized, the circuit for relay 10S being similar to those for relay 12S already traced.

- When the train vacates section 11T, current of reverse polarity is supplied to mechanism 12G over back contacts 54 and 50 of relay 10P and front contacts 52 and 53 of relay 10S, so that mechanism 12G assumes the caution position. Contact 57 of mechanism 12G closes, energizing relay 12P which again prepares the clear circuit for signal 4RA in the rear and by opening back contact 75 releases relay 12S.
- When the train enters section A10T, the circuit for relay 4RAR in advance of the train, as will be seen by placing Fig. 1B at the right of Fig. 1A, is opened at contact 94 of relay A10TR in Fig. 1A, since contact 80 of relay 2RAS which also connects terminal B to this circuit is now open. Relay 4RAR therefore releases, and at contact 67 completes the circuit for mechanism 4RAG to clear signal 4RA, provided the single track stretch in advance of that signal is unoccupied. Mechanism 4RAG upon becoming energized closes contact 95, thereby energizing relay 4RAP to operate contacts 29 and 38 to change the polarity of the current supplied to mechanism 2RAG from reverse to normal. Mechanism 2RAG therefore becomes energized in the normal direction, causing the indication of signal 2RA to change from caution to clear.
- When mechanism 4RAG becomes energized, its contact 96 opens the circuit for relay 4RAS, and contacts 97 and 98 of mechanism 2RAG in the circuit for relay 4RAS are opened when signal 2RA assumes the clear position. Relay 4RAS opens contacts 99 and 100 in the circuits for the opposing signal mechanisms 4LAG in Fig. 1B and 13G in Fig. 1C at the right of Fig. 1B. This mechanism 13G therefore assumes the stop position, releasing relay 13P and causing the mechanism 11G for the next intermediate signal 11 to move from clear to stop, and releasing relay 11P to open the circuits for the opposing head block signal such as signal 2LA at the righthand end of the single track stretch in advance thereby by extending the portion of track in which the traffic direction from left to right is established to include the single track stretch at the right of signal 4RA. Relay 4RAS also opens a contact in the circuit of a relay similar to relay 1WR for controlling the switch machine 3SM.
- When the train enters section 1T, signal 2RA again returns to stop, relay 2RAP releases and relay 2RAS becomes reenergized. Switch 1, however, remains locked because contact 106 of relay 1TR in the circuit for relay 1WR is open, and the closing of contact 91, and likewise the closing of contacts 88 and 89 of relay 2RAS in the circuits for the opposing signal mechanisms 2LAG and 4LAG, and the closing of its contact 90 in the circuit for relay 4RAR, is without effect at this time. Relay 1TR at back contact 110 completes a circuit for the directional stick relay 2RS which is closed momentarily from terminal B, back contacts 107, 108, 109 and 110 of relays 2LS, 2LAP, 2LBP and 1TR, front contact 111 of relay 2RAP to terminal C. Relay 2RS becomes energized and completes a temporary stick circuit which is the same as that just traced except that it includes the front contact 112 of relay 2RS in place of contact 111. Relay 2RS opens contact 113 in the circuit for the opposing signal mechanism 2LAG. Relay 2LAR releases when the train advances to section 2T, and closes contact 114 in the circuit for mechanism 2LAG. It will be seen that relay 2RS functions in such a manner as to prevent the circuit for mechanism 2LAG from becoming energized in response to

the release of relay 2LAR when that relay is released by a train moving from left to right. Relay 2RS is held energized as long as relay 2LAR is released by a stick circuit which includes its own front contact 115 and back contact 116 of relay 2LAR.

When the train vacates section A10T, mechanism 10G in Fig. 1C at the left of Fig. 1A becomes energized in the caution position, as shown, and relay 10P becomes energized, releasing relay 10S and causing mechanism 12G to assume the clear position, as shown, so as to permit a following train to pass through the single track stretch under permissive control in accordance with the usual practice in systems of this character.

When the first train enters section 3T, signal 5RA returns to stop, relay 4RAP releases and relay 4RAS becomes reenergized, and when the train enters section A13T, relay 4LAR releases. It is to be understood that the circuits for relays 4LS and 4RS are similar to those for relays 2RS and 2LS, respectively, and it follows that relay 4RS picks up when the train enters section 3T and is held energized by relay 4LAR as long as that relay is released. It follows, therefore, that the circuit for signal 4LAG is held open at contact 117 of relay 4RS as long as relay 4LAR is held deenergized by a train moving from left to right, and the closing of contact 118 of relay 4LAR in the circuit for mechanism 4LAG is rendered ineffective.

When the train vacates section 3T, the circuit for relay 2LAR is completed from terminal B at contact 101 of relay 4LAS over contacts 103, 104 and 105 of relays 3TR, 4TR and 2TR through relay 2LAR to terminal C, and therefore relay 2LAR becomes energized and relay 2RS releases. Similarly, the circuit for relay 4LAR is completed at contact 74 of relay 12TR when the train vacates section 12T, and then relay 4LAR becomes energized and relay 4LS releases.

It will be seen, therefore, that in accordance with the present invention a given direction of traffic when once established by a train is maintained past inactive sidings as well as through the single track stretches. It will be seen that the traffic direction from left to right is maintained by relay 2RS until the train vacates section 3T, and by relay 4RS until the train vacates section 12T just as it is maintained by relay 10S, associated with the automatic signal 10, until the train vacates section 1T. Under inactive control, with relays 2AB and 4AB energized, signals 2RA and 4RA may be employed as permissive "stop and proceed" signals like signals 10 and 12. Accordingly, these signals are provided with markers M having lamps ME. The circuit for marker lamp 2RME may be traced in Fig. 1A from terminal B over contacts 119 and 120 of relays 2AB and 2RS, lamp 2RME to terminal C, the circuit for the marker lamp 4RME, not shown, being similarly controlled by relays 4AB and 4RS.

In the foregoing I have traced the movement of a train from left to right from a left-hand section 3T through the successive track sections extending to a similar section 3T of an inactive passing siding at the right. The circuits for the opposite direction are similar, and the movement of a train from right to left may be similarly traced from any section 1T to a similar section 1T of the next siding to the left, as will be apparent from the drawings.

There remains to be considered the effect of

opposing train movements upon the system. It has already been pointed out that a train moving from left to right upon entering section 11T releases the reproach relay 2RAR, which relay 5 by closing contact 18 causes the second signal 2RA in advance to assume the caution position and signal 10 directly in advance to indicate clear, and that relay 2RAS is released and opens its contact 89 to hold signal 4LA at stop. Similarly, when an opposing train approaching the 10 same siding and occupying the single track stretch at the right of the siding enters section 12T, contact 14 of relay 12TR opens to release the approach relay 4LAR, and the latter relay 15 by closing its contact 118 completes the circuit for mechanism 4LAG so that signal 4LA assumes the caution position and its distant signal 13 indicates clear, and relay 4LAS is released and opens its contact 37 to hold signal 20 2RA at stop. It is evident from the circuits as already described that signals 2RA and 4LA at the opposite ends of the siding cannot both be cleared at the same time, and that the train which first enters the adjacent 25 approach zone will take precedence, and also that adequate stopping distance for the opposing trains may readily be provided. It will also be seen that similar conditions prevail in the case 30 of two opposing trains approach a single track stretch at the same time, and that signals 4RA and 2LA at opposite ends of the single track stretch cannot be both be cleared at the same time.

35 It will be apparent from the foregoing that under the inactive control condition the operator at the control office is relieved of the usual duty of manually clearing each head block signal in order to permit the movement of trains through the controlled territory, and that manual supervision is not required unless meeting points for opposing trains or passing points for train moving in the same direction are to be arranged.

40 I shall next describe the operation of the apparatus under manual control. The communication system may be of any suitable type, but as herein disclosed it is to be understood to be similar to the "Time Code" system as disclosed in a copending application, Serial No. 600,786, filed 45 March 23, 1932 by Lloyd V. Lewis, for Remote control systems, which corresponds with British Patent No. 415,787, issued September 3, 1934. In this system, the apparatus at the control office includes a plurality of control panels, one for each field station, each including a group of levers 50 as indicated in the left-hand portion of Fig. 2, for controlling the corresponding station devices, together with indication lamps for indicating the condition of these devices. A track diagram is also provided as indicated at the top in Fig. 2, 55 containing a plurality of lamps for indicating train movements through the territory. The code control of the switch and signal stick control relays at station No. 1 by the levers of the corresponding office panel, and also of the lamps of that panel and of the corresponding portion of the track diagram by the indication relays at station No. 1, is indicated diagrammatically by direct wire connections in Fig. 2, in order to 60 illustrate the operation of the various devices in a simple manner. It is to be understood that the devices at station No. 2 are similarly controlled and also that the station apparatus as shown in the Lewis application and patent has been 65 modified by the addition of the "active-inactive"

conditioning relay 2AB and its repeating relay 2ABP.

The code system operates in the following manner: To send a control code to station No. 1, the operator first moves the control levers 1WK, 5 2GK, etc. of the corresponding panel as required and then momentarily operates a starting key 1SK. The latter operation initiates the transmission of a code containing selecting elements for selecting station No. 1 and function elements 10 identifying the position of each of the levers of the corresponding panel. The selecting elements cause the momentary energization of a delivery relay 1D, thereby operating the station stick relays in accordance with the function elements 15 of the code, that is, to positions corresponding to the lever positions. Thus, for example, the operator may restore the apparatus at station No. 1 to the active condition by operating key 1SK when the levers 1WK, 2GK and 2UK 20 occupy the positions shown in Fig. 2, in which case the energization of relay 1D in response to the operation of key 1SK will merely open the stick circuit for relay 2US at back contact 121 to effect the release of that relay, thereby deenergizing relay 2AB by opening its circuit at contact 11. The operator may also send a single code, 25 for example, which will not only restore the apparatus at station No. 1 to its active condition but will also reverse switch 1 and clear signal 30 2RB to permit a train moving from left to right to enter the siding over switch 1, provided the train is at some distance from the switch so that the approach relay 2RAR is energized. In this case levers 1WK and 2GK are moved to the 35 right and key 1SK then operated to energize relay 1D momentarily. Relays 1NWS and 2US will release due to the opening of back contacts 122 and 121 of relay 1D. Relays 1RWS will pick up over front contacts 123 and 124 of relays 1D 40 and 1MP, and relay 2AB will release due to the opening of contact 11, completing a circuit over contacts 125 and 126 of relays 1D and 2AB to pick up relay 2RHS. When relay 1D is released, relays 1RWS and 2RHS are held energized over 45 their stick circuits including back contacts 122 and 127 of relay 1D.

55 Referring now to Fig. 1A, it will be seen that in response to the last mentioned code, relay 1WR becomes energized in the reverse direction 50 over front contact 128 of relay 1RWS and back contact 129 of relay 1NWS, and the left-hand contact 130 of relay 1WR opens, releasing relay 1NWP and thereby opening contact 16 in the circuit for mechanism 2RAG, 55 thereby preventing the actuation of that mechanism in response to the closing of front contact 31 of relay 2RHS. The closing of the right-hand contact 131 of relay 1WR causes the switch machine 1SM to operate switch 1 to reverse, and 60 when the switch becomes locked in that position, relay 1WP becomes energized in the reverse direction completing the circuit for relay 1RWP at its right-hand contact 132. Relay 1RWP picks up and completes the caution or slow speed 65 control circuit for signal 2RB, which may be traced from terminal B, front contact 32 of relay 1RWP, over front contacts 28, 27, 25, 31 and 15, mechanism 2RBG, and back contact 30 of relay 1NWP, to terminal C, so that signal 2RB 70 will display the proper slow speed indication to permit the approaching train to enter the siding.

75 If the operator should inadvertently attempt to effect these operations after the approaching train had released relay 2RAR and thereby 75

cleared signal 2RA, it will be seen that relay 2RAS will have been released by mechanism 2RAG and consequently relay 1MP in Fig. 2 will be released, the circuit for the latter relay being open at contacts 133 and 134 of relays 5 2RAS and 2RAR. Consequently when relay 1D is operated, relay 2RHS will become energized and relay 2AB will release, as already described, but the circuit for relay 1RWS will be held open 10 at contact 134 of relay 1MP and the stick circuit for relay 1NWS will be maintained closed by back contact 135 of relay 1MP. It follows by that the clear signal 2RA will not be interfered with, the circuit for mechanism 2RAG although 15 opened momentarily at front contact 17 of relay 2AB being closed again over back contact 17 and front contact 31 of relay 2RHS, so that the train is permitted to continue over the established route.

20. In either case, when the train enters section 1T, the signal is put to stop by the opening of contact 32 of relay 1TR in the circuits for mechanisms 2RAG and 2RBG, relays 1TZ and 2RHS being also released by the opening of contacts 25 26 and 135 of relay 1TR.

The release of relay 2RHS causes the signal to remain at stop after section 1T is vacated, but as explained in the Lewis application and patent hereinbefore referred to, this relay may 30 be reenergized by code after relay 1TZ releases and closes contact 136 in order to clear the signal for a following train, or relay 2RHS may be held energized to permit the signal to clear automatically by sending a code to energize relay 35 2US and 2RHS, so as to close contact 137 of relay 2US. In this case, relay 2AB is not operated in response to the energization of relay 2US because its circuit is held open at contact 13.

40. The station apparatus may be restored to its inactive conditions as shown by operating key 1SK with levers 1WK and 2GK normal, as shown, and with lever 2UK closed, thereby energizing relays 1NWS and 2US and releasing relays 1RWS 45 and 2RHS or 2LHS, if energized. If the track switch is reversed, it will be restored to normal and relay 2AB will become energized when the normal contact 14 of relay 1WP closes.

45. It will be clear from the foregoing that the 50 station apparatus may be placed in the active or inactive condition at will by the operator, subject to certain restrictions, so as to not interfere with train movements. With the apparatus in the active condition, the operator has 55 full control over the switches and signals but it will be apparent that the usual time and approach locking protection and the checking of opposing signals is effective not only under this condition but also when the apparatus has been 60 restored to its inactive condition and the clearing of the signals for either direction is effected automatically.

65. It may be desirable at times, as for example, in case of a failure of the communication system, to restore the station apparatus to its inactive condition by local means, and to illustrate this feature a push button EPB is provided in Fig. 2. As will be apparent from the drawing, push button EPB when operated will cause the 70 energization of relays 1NWS and 2US in response to the closing of its front contacts 133 and 139, while the opening of back contact 139 of push button EPB will cause relay 2LHS or 2RHS to release if energized, and the opening 75 of back contact 140 of relay 1NWS will cause

relay 1RWS to release if that relay is energized. It will be clear therefore that push button EPB when operated will cause the apparatus to assume its inactive condition as shown. Furthermore, the push button EPB may be replaced if 5 desired by a relay which is operated automatically in the event of a failure of the code line, such relays being shown, for example, in the Kemmerer Patent No. 1,940,913, granted December 26, 1933, and in the Baughman Patent No. 10 2,011,237, granted August 13, 1935, in which case the operator may also render all stations inactive manually by merely opening the code line at the control office.

15. It is to be understood that the transmission of indication codes by the field stations is effected in a manner generally similar to the transmission of control codes as above described, each code including elements for selecting the office panel assigned to the sending station, and other ele- 20

ments each of which is effective to light a particular indication lamp at the office if the corresponding indication contact at the sending station is closed, or to extinguish such lamp if the contact is open. An indication code is initiated 25 either by the momentary energization of a wire marked "start" in Fig. 2, or by means, not shown, acting in response to a change in position of any of the energized indication contacts, as explained in the Lewis application and patent hereinbefore 30 referred to. Thus, for example, if track section 1T becomes occupied, back contact 141 of relay 1TR will close to initiate a code to light the track indication lamp 1TE, as indicated by the dotted line connection in Fig. 2, and when section 1T is vacated, another code will be initiated to extinguish lamp 1TE. Each of these codes includes a switch indication element controlled by a circuit which includes front contact 142 of relay 1NWP and it follows that the normal switch in- 40

45. dication lamp 1NE is lighted as long as switch 1 is closed and locked in its normal position in correspondence with relay 1WR. The similar circuits governing the signal indication lamps 2LE, 2NE and 2RE, and the approach lamp 2RAE are 50 each normally open at back contact 143 of relay 2AB, and when the apparatus is in its inactive condition, as shown, each of these lamps remains dark. It is to be understood that the opening of back contact 143 prevents the initiation of indica- 55

55. tion codes in response to a change in position of any of the contacts in series therewith, such as contact 146 of the approach relay 2RAR or contact 145 of the signal mechanism 2RAG. Front contact 146 of relay 2AB, however, provides a 60 starting circuit closed momentarily over the back contact 147 of relay 2ABP when relay 2AB picks up, which initiates a code extinguishing the signal indication lamp when lighted, and the subsequent closing of back contact 146 when relay 2AB is released initiates another code and completes circuits over contact 148 and over one or both of the contacts 145 and 148 of mechanisms 2RAG and 2RBG to restore the signal indication light 65 to correspond with the condition of the signals. It will be seen that this arrangement provides a distinctive indication of the position of relay 2AB, the signal and approach indication lamps being dark when the station apparatus is in the inactive condition, while lamp 2LE, 2NE or 2RE 70 is lighted and lamp 2RAE is rendered responsive to the condition of relay 2RAR when the station apparatus is in the active condition. Relay 2AB, however, preferably does not govern the circuits for the switch indication lamps 1NE and 1RE for 75

the reason that when the station is inactive, these relays do not initiate codes as long as the apparatus is in order and the track switch remains locked and it is desirable to retain the switch indications so that the operator will be promptly advised if any defect develops causing the release of relay 1NWP, so that the defect may be more promptly corrected.

It will be seen therefore that station No. 1 in the inactive condition is simply an "OS"ing point" for reporting the passage of trains. It is to be understood that generally the movement of trains through the successive switch sections such as section 1T will be recorded on a train graph at the office, as explained in the Lewis application and patent.

The apparatus at station No. 2 may control the apparatus of the second office panel in a similar manner, but with the sidings closely spaced an "OS" indication from one end only may suffice. The circuit for lamp 3TE, for example, may be controlled over a back contact of the corresponding relay 4AB, in which case both lamps 3TE and 4LAE will remain dark when a train passes station No. 2 in the inactive condition, thereby still further reducing the number of codes to be transmitted.

I shall now assume that there are two trains approaching from opposite directions, that the apparatus is in the inactive condition as shown, and that the operator is required to effect a meet at the siding of Figs. 1A and 1B, the train moving from right to left taking the siding. It will be evident that signal 2RA will clear automatically and that the train moving from left to right may pass signal 2RA at clear without any action by the operator who will, however, be required to send a code to put station No. 2 in the active condition, which code will also serve to reverse switch 3 and to then clear signal 4LB. This code will be followed immediately by an indication code from station No. 2, indicating that switch 3 is in transit, and a second indication code will be transmitted when switch 3 reverses and signal 4LB clears. A third indication code will be transmitted when the train passing signal 4LB enters section 3T, and a fourth when the train vacates that section. The operator will send a second control code to restore station No. 2 to the inactive condition as soon as he is informed that the train entering the siding has vacated section 3T, whereupon an indication code indicating that condition will be transmitted and signal 4RA will clear automatically for the opposing mainline train. An indication code will be transmitted from station No. 1 when the train moving from left to right enters section 1T and another when it vacates that section. As soon as the last named code is received, the operator will send a third control code to put station No. 1 in the active condition, this code also serving to reverse switch 1 and to clear signal 2LB, which code will be followed by four indication codes indicating respectively that switch 1 is in transit, that it is locked reverse and signal 2LB has cleared, that the train governed by signal 2LB has entered section 1T and put that signal to stop, and that that train has vacated section 1T. Upon receipt of the last named indication code, the operator will send a fourth control code restoring station No. 1 to the inactive condition and this in turn will be followed by an indication code from that station. No further action on the part of the operator is required to complete the movement of the two trains out of the controlled ter-

itory. On the other hand, if all the remaining stations were active, as in centralized traffic control systems, as heretofore used, the operator would be required to send a control code to each such station to reverse the direction of traffic and to clear the signal at that station and each such code would be followed by a corresponding indication code indicating the clearing of the signal.

The advantages of the inactive control are self evident. It may be shown, for example, that the number of codes required to move trains through a territory of the usual extent, with all stations active as has heretofore been the practice in this art, will be from four to six times as great as 15 when all stations are arranged to be normally inactive as above described and the operator is required to send codes only when meets are to be effected, and it will be seen that the volume of traffic which the system can control is correspondingly increased by the practice of my invention.

I shall now describe the second form of my apparatus as illustrated in Figs. 3A, 3B and 1C. This differs from the first form principally in that 25 the head block signals 2RA, 2LA, 4RA and 4LA, and the intermediate signals 10, 11, 12 and 13 are normally clear when the station apparatus is in the inactive condition, while in the first form, the signals are cleared only when a train 30 is approaching. It is to be understood that the circuits are similar to those hereinbefore described except for such modifications as are required to provide for normal clear operation, and these modifications will be described as the 35 description proceeds.

Starting with the assumptions that relays 2AB and 4AB are energized so that the stations are in the inactive condition and that a train moving from left to right occupies a left-hand section 40 3T, by placing Figs. 1C and 3A in order at the right of Fig. 3B, it will be seen that the circuit for mechanism 13G is open at contact 71 of relay 3TR and consequently the circuits for mechanisms 11G and 2LAG are also open and the opposing signals 13, 11 and 2LA in advance indicate stop. Signal 12 is at clear, as shown, and assuming signal 2RA in advance to be at clear or caution, signal 10 will be at clear. The circuit for mechanism 10G may be traced from 50 terminal B, contact 46 of relay 2RAP, Fig. 3A, contact 149 of relay 2LS, the closed front contact 45 of relay 2LAS, the closed back contact 150 of mechanism 2LAG, contacts 44, 43 and 42 of relays 1TR, A10TR and 10TR, mechanism 10G, 55 contact 41 of relay 2RAP, to terminal C. In order to consider conditions in advance of signal 2RA, drawings 3B and 1C may be placed in order at the right of Fig. 3A, and it will then be seen that the circuits for signal 4RA are similar 60 to those for signal 2LA, above referred to, and that if a train moving from right to left is approaching in a section at the right of section 12T, signal 4RA will be at stop and consequently signal 2RA will be at caution. The circuit for 65 mechanism 2RAG may be traced in Figs. 3B and 3A from terminal B, back contact 29 of relay 4RAP, front contact 30 of relay 1NWP, mechanism 2RAG, contacts 16, 17, 19, 31, 27, 28, 32, 33, 34, 35, 36, contact 151 of a stick relay 4ABS, 70 contact 152 of relay 4LAR, back contacts 153 and 38 of relays 4LS and 4RAP to terminal C.

Since signal 2LA is at stop, relay 2LAP is de-energized and the circuit for mechanism 4LAG similar to the one for mechanism 2RAG just 75

traced is in a similar condition and signal 4LA is at caution. That is, when two trains are approaching the same siding from opposite directions but neither has entered the adjacent approach zone, the two entering signals 2RA and 4LA will both indicate caution. Relay 4LAS is therefore released, but its contact 37 which governs the circuit for mechanism 2LAG under the active condition as in the first form of the apparatus is now bridged by contact 154 of a relay 4ABS which relay is energized over contact 154 of relay 4AB, as shown in Fig. 3B. The corresponding open contact 29 of relay 2RAS in the circuit for mechanism 2LAG is similarly bridged by contact 155 of relay 2ABS, which relay is energized over contact 164 of relay 2AB.

If now the train approaching signal 2RA at caution enters section 11T in Fig. 1C at the left of Fig. 3A before the train approaching signal 4LA at caution enters section 12T, in Fig. 1C at the right of Fig. 3B, signal 4LA will be put to stop and signal 2RA held at caution for the reason that when the train moving from left to right enters section 11T, relay 2RAR is released by the opening of contact 83 of relay 11TR, thereby opening contact 156 of relay 2RAR in the circuit for mechanism 2LAG. Signal 4LA will therefore assume the stop position and back contact 157 of mechanism 2LAG will close to bridge contact 152 of relay 4LAR to maintain the caution circuit for signal 2RA closed after the opposing train approaching the siding from the right occupies section 12T, and by opening contact 14 of relay 12TR releases relay 4LAR. It follows that the trains in this case will be held at signals 4RA and 4LA, respectively. It will be seen that the arrangement is such that when two trains are approaching a siding from opposite directions, each will first encounter a caution signal and that adequate stopping distance may be provided to prevent either train from overrunning a stop signal.

Similar conditions prevail with regard to movements through the two sidings at opposite ends of the single track stretch when two trains are approaching these sidings from opposite directions. Considering first the siding at the left-hand end of the stretch, and placing Fig. 3B at the right of Fig. 3A, it will be seen that when a train moving from left to right and approaching signal 2RA at caution or clear enters section A10T, relay 4RAR is released by the opening of contact 94 of relay A10TR since relay 2RAS is deenergized and contact 96 is open, and if signal 4RA at the left-hand end of the single track stretch is at clear or caution, relay 4RAR by opening contact 158, Fig. 3B, in the circuit for mechanism 13G, in Fig. 1C at the right of Fig. 3B, causes the opposing signals 13, 11 and 2LA at the right of the siding which the train is approaching to assume the stop position. On the other hand, if signal 4RA is at stop, contact 158 of relay 4RAR is bridged by back contact 159 of relay 4RAG and the opposing signals are not interfered with by the release of relay 4RAR by a train moving from left to right.

Considering next that drawings 3A and 3B represent the siding at the right-hand end of the single track stretch under discussion, it will be seen that when a train moving from right to left and approaching signal 4LA at caution or clear enters section A13T, relay 2LAR is released by the opening of contact 102 of relay A13TR, and if signal 2LA at the right-hand end of the single track stretch is at clear or caution,

relay 2LAR by opening contact 160, Fig. 3A, in the circuit for mechanism 10G, in Fig. 1C at the left of Fig. 3A, causes signals 10, 12 and 2RA at the left of the siding which the train is approaching to assume the stop position, but if signal 4LA is at stop, contact 160 is bridged by contact 150 of relay 2LAG, and the opposing signals are not interfered with by the release of relay 2LAR by a train moving from right to left. It will be seen that if two opposing trains approach adjacent sidings simultaneously and the train moving from left to right causes the opposing signal 2LA at the right-hand end of the single track stretch in advance of the siding to assume the stop position before the corresponding relay 2LAR is released by the opposing train, back contact 150 of mechanism 2LAG at the right-hand end of the single track stretch will close before contact 160 of relay 4LAR opens and the train moving from left to right may continue through the single track stretch and the trains will be held at signals 2RA and 2LA, respectively.

The control limits for the signals in this form of the apparatus are overlapped in this manner when the stations are inactive to prevent trains from simultaneously passing opposing clear signals at the opposite ends of a block and it follows that since the control limits extend further under inactive control than in the first form of the apparatus, a change from inactive to active control involves a shift in the control limits.

It will be assumed that the signals at station No. 1 are manually put to stop by sending a code to render that station active by the release of relay 2AB, with relays 2RHS and 2LHS remaining deenergized. Signals 2RA and 2LA will be put to stop by the opening of front contacts 17 and 18 of relay 2AB and contacts 162 and 163 of relay 2AB will bridge contacts 160 and 156, respectively, of relays 2RAR and 2LAR to cut out the above described overlap in the control limits for signals 10 and 4LA, but each of the relays 2RAS and 2LAS will remain deenergized and its contact 45 or 89 in the control circuit for signal 10 or 4LA will remain open until relay 2RAS or 2LAS becomes energized following the return of the associated signal 2RA or 4LA to the stop position. Relay 2ABS prevents the temporary opening of the circuits for signals 10 and 4LA under this condition. Thus after relay 2AB is released and opens its contact 164, relay 2ABS is held energized over contact 165 of relay 2LAS and also over contact 166 of relay 2RAS, and consequently the circuits for signals 10 and 4LA are held closed at contacts 167 and 155 of relay 2ABS until these contacts are bridged by contacts 45 and 89, respectively, of relays 2LAS and 2RAS. The circuits for signals 2RA and 13 are controlled in a similar manner by relays 4AB and 4ABS. It will be apparent that after relays 2ABS and 4ABS release, the opposing signal control is similar to that hereinbefore described in connection with Figs. 1A and 1B and that the second form of the apparatus functions in the same manner as the first form when in the active condition.

Although I have herein shown and described but two forms of railway traffic controlling apparatus embodying my invention, it is understood that various changes and modifications may be made therein within the scope of the appended claims without departing from the spirit and scope of my invention.

Having thus described my invention, what I claim is:

1. In a centralized traffic control system for

- railroads, a control office, a plurality of stations at spaced points along a railway track, traffic controlling apparatus at each station, normally inactive transmitting means at each station normally operable to transmit to the control office indications only of certain traffic conditions in response to changes in traffic conditions at that station, a conditioning relay at each station manually controllable from the control office, and means controlled by each conditioning relay for conditioning the transmitting means at the same station to transmit additional indications automatically in response to changes in the condition of the apparatus at such station.
2. In a centralized traffic controlling system for railroads, a control office, a plurality of stations at spaced points along a railway track, a plurality of traffic governing devices at each station, normally inactive apparatus at each station normally operable to transmit to the control office indications only of certain traffic conditions at such station, conditioning means at each station manually controllable from the control office, and means effective only when said conditioning means is in a given condition to render the apparatus at such station operable to transmit additional indications to indicate the condition of the devices at such station automatically whenever a change in such condition occurs.
3. In a centralized traffic control system for railroads, a control office, a plurality of stations at spaced points along a railway track, a plurality of traffic governing devices at each station, indication means for such devices at the control office, normally inactive transmitting apparatus at each station, conditioning means manually controllable from the control office to selectively render the transmitting apparatus at a selected station active or inactive, means controlled by said transmitting apparatus only when active for automatically controlling the indication means for the devices at such station in accordance with the condition of such devices whenever any change in such condition occurs, and means controlled by each transmitting means for distinctively controlling the indication means for the devices at the corresponding station to indicate at the office whether such transmitting means is active or inactive.
4. In combination, an office and a station, two groups of traffic governing devices at said station, a transmitter at said station effective when operated to transmit indications to the office indicating the condition of said devices, means operating said transmitter automatically whenever a change in such condition occurs, a conditioning relay, and means controlled by said relay for conditioning said transmitter to transmit indications of one group only of said devices and for rendering said transmitter non-responsive to changes in the condition of the devices of the other group.
5. In combination, an office and a station, a track section at said station, signals for governing traffic movements over said section, a transmitter at the station normally effective when operated to transmit an indication of the condition of said track section to the control office in response to a change in such condition, control relays manually governed from the control office for controlling said signals, a conditioning relay at said station, means effective when said conditioning relay is in one position for controlling said signals automatically in accordance with traffic conditions without energizing said control relays,
- and means effective when said conditioning relay is in its other position for selectively conditioning said transmitter to transmit an additional indication during each operation thereof to indicate the condition of said signals at the control office.
6. In a centralized traffic control system for railroads, a control office, a plurality of stations at spaced points along a railway track, a track section at each station, signals at each station for governing traffic movements over such section, indication means at the office for each station for indicating the condition of the track sections and signals, a transmitter at each station normally effective when operated to transmit an indication of the condition of the track section at such station to the office in response to a change in such conditions, control relays at each station manually governed from the office for controlling the signals, a conditioning relay at each station, means effective when the conditioning relay at a station is in one position for controlling the signals automatically in accordance with traffic conditions without energizing the control relays at such station, means effective when the conditioning relay at a station is in its other position for selectively conditioning the associated transmitter to control the indication means for the signals at such station in accordance with the condition of such signals to indicate that such signals are subject to manual control, and means at the office for selectively controlling said conditioning relays.
7. In combination, a stretch of railway track comprising a plurality of successive track sections a track relay for each section, signals at spaced points in said stretch, control circuits controlled by said track relays for clearing said signals automatically in accordance with traffic conditions in said stretch, a control office, a control relay for each signal governed from the office for imposing manual control upon such signal, transmitting means for each signal for automatically transmitting indications of its condition and of the condition of the adjacent track section to the office, means at the office for continuously displaying such indications, a conditioning relay for each signal, means effective when each conditioning relay is operated to a given position for cancelling the indication of the corresponding signal at the office, means effective as long as such conditioning relay remains in said given position for rendering the associated signal automatically responsive to the condition of its control circuit without energizing its control relay and for also preventing the transmission of indications of such signal to the control office, and means for selectively controlling said conditioning relays.
8. In combination, a stretch of railway track comprising a plurality of successive track sections, a track relay for each section, signals at spaced points in said stretch, control circuits controlled by said track relays for clearing said signals automatically in accordance with traffic conditions in said stretch, a control office, a control relay for each signal governed from the office for imposing manual control upon such signal, a conditioning relay for each signal, means effective only when a conditioning relay is in a given position for rendering the associated signal automatically responsive to the condition of its control circuit without energizing its control relay, and means including the control relays and manually controllable from the con-

trol office for selectively controlling said conditioning relays.

9. In combination, a stretch of railway track having a track switch at each end, signals at the ends of the stretch for governing traffic movements over the stretch, circuits for clearing said signals in accordance with the position of said track switches, a control office, a control relay for each signal governed from said office for imposing manual control upon said signals, means governed from the control office for controlling each track switch, a conditioning relay at each end of the stretch, means effective only when a conditioning relay is in a given position for rendering the associated signal automatically responsive to the condition of its control circuit without energizing its respective control relay, means manually controllable from the control office for selectively controlling said conditioning relays, and means preventing the operation of each conditioning relay except when the associated track switch is in a given position.

10. In combination, a stretch of single track railway including a block section, signals at the ends of said block section for governing traffic movements through said section, a locking relay for each signal energized only when such signal indicates stop, an approach relay for each signal energized only when an adjacent portion of the stretch in the rear of such signal is unoccupied, a control relay for each signal, means for manually governing each control relay, a circuit for clearing each signal controlled by a front contact of its control relay and by a front contact of the locking relay for the signal at the other end of the block section, a conditioning relay for each signal, means controlled by each conditioning relay in its operated position for completing the circuit for the associated signal in response to the release of the approach relay for such signal without energizing the control relay for such signal, and means for selectively controlling said conditioning relays.

11. In combination, a stretch of railway track having a track switch at each end, two signals including one at each end of the stretch for governing traffic movements through the stretch, a locking relay for each switch which when deenergized prevents operation of the switch, means for energizing each locking relay effective only when the associated signal is at stop, a manually governed control relay for each signal, a circuit for each signal governed by its control relay in accordance with the position of the adjacent track switch and closed only when the locking relay for the switch at the opposite end of the stretch is energized, a manually controllable conditioning relay at each end of the stretch, and means controlled by each conditioning relay when in a given position for completing the circuit for the signal at the same end of the stretch to permit such signal to clear without energizing its control relay when a train is approaching within a predetermined distance of such signal.

12. In combination, a stretch of single track railway having a track switch at each end, a main line signal and a siding signal at each end of the stretch for governing traffic movements from a main line section and from a siding, respectively, into said single track stretch, a locking relay for each switch which when deenergized prevents operation of the switch, means for energizing each locking relay effective only when the associated signals are at stop, manually

governed control relays for said signals, a circuit for each signal governed by its control relay in accordance with the position of the adjacent track switch and closed only when the locking relay for the switch at the opposite end of the stretch is energized, a manually controllable conditioning relay at each end of the stretch, and means controlled by each conditioning relay when in a given position for completing the circuit for the main line signal at the same end of said stretch to permit each such signal to be cleared automatically by an approaching train without energizing its control relay provided there is no opposing train approaching within a predetermined distance of the other main line signal.

13. In combination, a stretch of single track railway including a block section, signals at the ends of said block section for governing traffic movements through said section, a locking relay for each signal energized only when such signal indicates stop, an approach relay for each signal energized only when an adjacent portion of the stretch in the rear of such signal is unoccupied, a circuit for clearing each signal controlled in accordance with traffic conditions in said block section, and means effective under one condition for closing the circuit for each signal provided the approach relay for the signal at the other end of the block section is energized and effective under another condition provided the locking relay for the signal at the other end of the block section is energized.

14. In combination, a stretch of single track railway including a block section, signals at the ends of said block section for governing traffic movements through said section, a locking relay for each signal energized only when such signal indicates stop, an approach relay for each signal energized only when an adjacent portion of the stretch in the rear of such signal is unoccupied, a control relay for each signal, means for manually governing each control relay, a circuit for clearing each signal controlled by a front contact of its control relay and by a front contact of the locking relay for the signal at the other end of the block section, a conditioning relay for each signal, means controlled by each conditioning relay in its energized position for completing the circuit for the associated signal without energizing the control relay for such signal or the locking relay for the other signal provided the approach relay and the conditioning relay for the other signal are both energized, and means for selectively controlling said conditioning relays.

15. In combination, a stretch of single track railway including a block section, signals at the ends of said block section for governing traffic movements through said section, a locking relay for each signal energized only when such signal indicates stop, an approach relay for each signal energized only when an adjacent portion of the stretch in the rear of such signal is unoccupied, a control relay and a conditioning relay for each signal, means for manually governing each control relay and conditioning relay, means for clearing each signal when its control relay and the locking relay for the other signal are both energized and the conditioning relays for both signals are in a first position, and means for clearing each signal without energizing its control relay when the approach relay for the other signal is energized and the conditioning relays for both signals are in a second position.

16. In combination, a stretch of single track railway including a block section and an approach zone at each end of said block section, signals at the ends of said block section for governing traffic movements through said section, a control relay, a conditioning relay and a locking relay for each signal, means for manually governing each control relay and conditioning relay, means for energizing each locking relay only 5
 5 when the associated signal is at stop, means effective when the conditioning relays at the two ends of the stretch are in one position for clearing each signal automatically provided the block section and the approach zone at the end remote
 10
 15 from such signal are both unoccupied, and means effective when said conditioning relays are in another position for clearing each signal manually in accordance with traffic conditions in said block section provided the locking relay at the end remote 15
 20 from such signal is energized.

17. In combination, a stretch of single track railway including a block section and an approach zone at each end of said block section, signals at the ends of said block section for governing traffic movements through said section, a control relay, a conditioning relay and a locking relay for each signal, means for manually governing each control relay and conditioning relay, means for energizing each locking relay 25
 25 only when the associated signal is at stop, means effective when the conditioning relays at the two ends of the stretch are in one position for clearing each signal automatically provided the block section and the approach zone at the end remote
 30 from such signal are both unoccupied, and means effective when said conditioning relays are in another position for clearing each signal manually in accordance with traffic conditions in said block section provided the locking relay at the end remote 30
 35 from such signal is energized, and means effective when each conditioning relay assumes such other position for rendering the associated locking relay ineffective to control the signal at the other end of the block section until 40
 45 such locking relay becomes energized.

18. In combination, a stretch of railway track including a block section and an adjacent approach section, a signal for governing traffic movements from said approach section into said block section, a control relay for imposing manual control upon said signal, a manually controlled conditioning relay, an approach relay energized only when said approach section is unoccupied, a circuit for clearing said signal controlled in accordance with traffic conditions in said block section and closed when said control relay is energized provided said block section is unoccupied and said conditioning relay is in one position, and means effective when said conditioning relay is in another position and said control relay is deenergized for closing said circuit automatically in response to the release of said approach relay by a train approaching said signal.

19. In combination, a stretch of railway track including a block section and an adjacent approach section, a signal for governing traffic movements from said approach section into said block section, a control relay for imposing manual control upon said signal, a manually controlled conditioning relay, an approach relay energized only when said approach section is occupied, a directional stick relay, means for energizing said stick relay as long as said approach section is occupied by a train moving

away from said block section, a control circuit for clearing said signal controlled in accordance with traffic conditions in said block section and closed when said control relay is energized provided said block section is unoccupied and said conditioning relay is in one position, and means effective when said conditioning relay is in another position and said control relay and said stick relay are both deenergized for closing said control circuit automatically in response to the release of said approach relay.

20. In combination, a track section having a track relay, an approach section adjacent said track section, a signal for governing traffic movements from said approach section into said track section, an approach relay which becomes deenergized when said approach section is occupied, a stick relay, a pickup circuit for said stick relay controlled by a back contact of said track relay, a stick circuit for said stick relay controlled by a back contact of said approach relay, and a control circuit for said signal controlled by a front contact of said track relay and back contacts of said approach relay and of said stick relay.

21. In a centralized traffic control system for railroads, a stretch of single track railroad including a plurality of passing sidings each having a power operated track switch at each end, signals at spaced points in said stretch for governing traffic movements through said stretch in both directions, a communication system for effecting manual control of said switches and signals comprising a plurality of field stations connected with a control office by line wires, each field station being adjacent a different track switch, a plurality of track sections in said stretch each having a track relay, signal control circuits for said signals controlled by said track relays and normally effective to clear said signals automatically to permit train movements through said stretch in one direction or the other over the track switches in their normal position, means for automatically initiating the operation of said communication system to transmit indications of train movements through each track section in said stretch which includes a track switch and also to indicate the position of any track switch which becomes displaced from its normal position, means including said communication system for selecting a particular field station and for controlling the track switch and signals adjacent such switch manually from the control office, and means for automatically initiating the operation of said communication system to transmit indications of the clear and stop positions of said manually controllable signals to said control office effective only so long as said signals are being controlled manually.

22. In combination, a detector section of railway track including a track switch, approach sections adjoining the ends of said detector section, a signal at each end of said detector section for governing traffic movements from the adjacent approach section into said detector section, a circuit for clearing each signal controlled in accordance with the position of the track switch and closed only when the detector section and the approach section at the end thereof remote from such signal are unoccupied and the opposing signal is at stop, a directional stick relay for each signal, a pickup circuit for each stick relay closed when said detector section becomes occupied provided the associated signal is then clear and the opposing signal and its

stick relay are deenergized, an approach relay for each signal energized only when the approach section adjacent such signal is unoccupied, stick circuit means for holding the stick relay for each signal energized as long as said detector section is occupied or the approach relay for the opposing signal is deenergized, and means for automatically closing the circuit for each signal comprising back contacts of the approach relay for such signal and of the stick relay for the opposing signal.

23. In combination, a detector section of railway track including a track switch, approach sections adjoining the ends of said detector section, a signal at each end of said detector section for governing traffic movements from the adjacent approach section into said detector section, a circuit for clearing each signal controlled in accordance with the position of the track switch and closed only when the detector section and the approach section at the end thereof remote from such signal are unoccupied and the opposing signal is at stop, a directional stick relay for each signal, a pick-up circuit for each stick relay closed when said detector section becomes occupied provided the associated signal is then clear and the opposing signal and its stick relay are deenergized, an approach relay for each signal energized only when the approach section adjacent such signal is unoccupied, stick circuit means for holding the stick relay for each signal energized as long as said detector section is occupied or the approach relay for the opposing signal is deenergized, means for automatically closing the circuit for each signal to permit an approaching train to enter said detector section, a marker lamp associated with each signal, and means controlled by each stick relay when energized for lighting the marker lamp for the associated signal to indicate the direction of

movement of said train after it has passed said signal.

24. In combination, a detector section of railway track including a track switch, approach sections adjoining the ends of said detector section, a signal at each end of said detector section for governing traffic movements from the adjacent approach section into said detector section, a circuit for clearing each signal controlled in accordance with the position of the track switch and closed only when the detector section and the approach section at the end thereof remote from such signal are unoccupied and the opposing signal is at stop, a directional stick relay for each signal, a pickup circuit for each stick relay closed when said detector section becomes occupied provided the associated signal is then clear and the opposing signal and its stick relay are deenergized, an approach relay for each signal energized only when the approach section adjacent such signal is unoccupied, stick circuit means for holding the stick relay for each signal energized as long as said detector section is occupied or the approach relay for the opposing signal is deenergized, a manually controlled conditioning relay, means effective when said conditioning relay is in one position for manually closing the circuits for said signals to clear one signal or the other, means effective when said conditioning relay is in another position for automatically closing the circuit for each signal comprising back contacts of the approach relay for such signal and of the stick relay for the opposing signal, a marker lamp associated with each signal, and means controlled by said conditioning relay in said another position and by each stick relay when energized for lighting the marker lamp for the associated signal.
